NOZZLE FOR VACUUM CLEANERS

Axel Albert Forsberg, Stora Essingen, Stockholm,
Sweden, assignor to Electrolux Corporation,
Dover, Del., a corporation of Delaware

Application August 31, 1938, Serial No. 227,607
In Sweden September 2, 1937

1 Claim. (Cl. 15—158)

This invention relates to nozzles for vacuum cleaners, and more particularly, to nozzles provided with a brush secured around the rim of the nozzle mouth.

In nozzles of this type, the brush must not be made too compact because it tends to prevent the dust and dirt from entering the nozzle. On the other hand, the brush must not be too open because it will reduce the suction available for lifting the dirt from the surface being cleaned.

An object of my invention is to provide a brush for use with vacuum cleaner nozzles to permit the ready entrance of the dirt and dust into the nozzle without, at the same time, too greatly reducing the suction available for lifting the dirt and dust.

What I consider to be novel and my invention may be better understood by reference to the following specification and appended claim when considered in connection with the accompanying drawing, in which

Fig. 1 is a front elevation of the improved nozzle;

Fig. 2 is a bottom view;

Fig. 3 is an enlarged sectional view taken along line 3—3 of Fig. 1;

Fig. 4 is a sectional view taken along line 4—4 of Fig. 2;

Fig. 5 is an enlarged detailed view of a portion of Fig. 4; and

Figs. 6 and 7 show two alternative arrangements of the brush sections along the forward edge of the nozzle.

Referring to the drawing, 10 indicates a nozzle body which is connected with an air conduit 11 by means of an elbow 12. Depending from the rear edge of the mouth of the nozzle body 10 is a brush section 13. The brush section 13 consists of bundles of bristles which are tightly compacted and extend along the rear edge of the nozzle body 10 between its two ends. The brush section 13 conforms to the shape of the rear edge of the nozzle body 10. At the end, shown at the left in Fig. 2, a brush section 14 is secured extending outwardly at an angle to the bottom surface of the nozzle body 10. A similar brush section 15 is secured to the opposite end of the nozzle body 10, shown at the right in Fig. 2. Depending from the forward edge of the nozzle body 10 are a plurality of brush sections 16 to the left of the center line of the brush, and brush sections 17 to the right. Brush sections 16 are of triangular shape with the apex of the triangle extending forward in the normal direction of movement of the nozzle body 10. The brush sec-

tions 17 may be described as of wedge shape with the small side of the wedge extending forward. The brush sections 16 are formed by six bundles of bristles with the exception of the brush section 16' at the extreme left which has only three bundles of bristles. The brush sections 17 are formed of nine bundles of bristles. The brush sections 13, 14, 15, 16, and 17 are mounted in a plate 18 secured to the nozzle body 10 by means of screws 19.

In the cleaning of a floor, rug, or other surface, the nozzle body 10 is moved forwardly over the surface to be cleaned. The suction produced by the vacuum cleaner, not shown, is communicated to the nozzle body 10 by means of the conduit 11 and elbow 12. Elbow 12 communicates with an opening 20 in the bottom of the nozzle body 10. As the nozzle body 10 is moved forwardly over the surface being cleaned, air is drawn in between the brush sections 16 and 17, and due to the triangular or wedge shape, respectively, of these brush sections, an injector action is produced increasing the velocity of the air as it enters in the region of the nozzle mouth. The high velocity air passes close to the surface being cleaned, raises the dirt and dust located on the surface, and carries it into the region of the nozzle mouth. The tightly compacted brush section 13 secured to the rear edge of the nozzle body 10 prevents this dirt and dust from passing beneath the nozzle mouth as the nozzle body 10 is moved forwardly. It is not anticipated that under ordinary circumstances, brush sections, triangular in shape, such as brush sections 16 and wedge shaped brush sections, such as brush sections 17, should both be provided on the forward edge of the nozzle body 10. Either of these forms of brush sections may be used as desired but the brush sections would ordinarily be uniform throughout the length of the forward edge. The forward edge 21 to which the brush sections 16 and 17 are secured is formed in a straight line to permit cleaning close to the edge of wood-work, furniture, and the like. The inclined ends 45 of brush sections 16 and 17 also facilitates cleaning close to obstacles without the necessity of contact between the brush nozzle body 10 and the obstacle. The rear edge 22 to which the brush section 13 is secured is formed with a compound 50 curve substantially convex to provide a greater width for the nozzle mouth at the center than at the two ends. This tends to equalize the difference in the air flow and suction at the two ends most remote from the central opening 20 and at 55 the center.

A plate 23 is secured to the nozzle body 10 by means of screws 24. Plate 23 is provided with an upturned flange 25 extending around its sides and edges and positioned closely adjacent to the brush sections. The flange 25 prevents the brush sections from being forced inwardly, due to friction, as the nozzle is moved along the surface being cleaned, and also, seals the top portion of the brush sections to insure a flow of air along the surface being cleaned. Plate 23 is provided with a central elongated opening 26 which registers with the opening 20. A rubber bumper 27 is secured around the edge of the plate 18 in which the brush sections are mounted. Bumper 27 has an inturned flange 28 which is clamped between the nozzle body 10 and the plate 18. A collar 29 extends upwardly from the flange 28 engaging a shoulder 30 provided around the inner edge of the nozzle body 10. The collar 29 prevents the bumper 27 from slipping out of position. A portion of bumper 27 extends downwardly overlying a portion of the brush sections. To prevent the depending portion of bumper 27 from forcing the two end brush sections 14 and 15 inwardly, a protecting plate 31, shown in Fig. 5, is secured to the two ends of the nozzle body 10 between the bumper 27 and the brush sections 14 and 15. Elbow 12 is pivotally secured to the nozzle body 10 by means of an annular ring 32 shown in Fig. 3 which seats in cooperating recesses in the elbow 12 and body 10.

Obviously, a number of arrangements of brush sections may be used to produce the desired effect of the brush sections 16 and 17. By way of exam-

ple, two such arrangements are shown in Figs. 6 and 7. In Fig. 6, the brush sections 33 are secured to the front edge 21 at an angle thereto producing inclined openings 34 between the brush sections 33. It will be noted that looking from the front toward the leading edge 21, the brush sections 33 completely cover the extent of the leading edge. A somewhat similar result is accomplished by the arrangement, shown in Fig. 7, in which alternate brush sections 35 and 36 are reversed with respect to the positioning of the apices of the triangular sections. In a like manner, looking at the front edge 21 of Fig. 7 the complete extent of the forward edge is covered by the brush sections 35 and 36. The air entering the nozzle mouth passes in opposite directions on the two sides of the brush sections 35. It is apparent that other arrangements of brush sections may be used in those illustrated herein, but it is to be understood that this invention is not limited to these specific arrangements. Other arrangements may be used within the scope of this invention as pointed out in the appended claim.

What I claim is:

A nozzle for vacuum cleaners including a nozzle body having a suction opening, closely packed brush bristles depending from the rear edge and two ends of the nozzle body around said suction opening, and closely packed brush bristles secured in sections extending in spaced relation from the forward edge of the nozzle body, said brush sections having a triangular cross-section with the apex of the triangle extending forwardly.

AXEL ALBERT FORSBERG.
